CLAIM

The ornamental design for a shovel, as shown and described.

DESCRIPTION

FIG. 1 is a top and right side perspective view of a shovel showing my new design;

FIG. 2 is a top plan view thereof;

FIG. 3 is a right side elevational view, the side opposite being a mirror of that shown;

FIG. 4 is a front elevational view thereof;

FIG. 5 is a rear elevational view thereof; and,

FIG. 6 is a bottom plan view thereof.
